UNITED STATES PATENT OFFICE.

SAMUEL THOMAS WALKUP, OF NEW YORK, N. Y.

PRESS THROW-OUT.

1,378,742.

Specification of Letters Patent. Patented May 17, 1921.

Application filed October 21, 1919. Serial No. 332,221.

To all whom it may concern:

Be it known that I, SAMUEL THOMAS WALKUP, a citizen of the United States, and resident of city of New York, in the county 5 of New York and State of New York, have invented a certain new and useful Press Throw-Out, of which the following is a specification.

This invention relates to a throw-out 10 mechanism for presses being intended more particularly for application to a press for artificial flowers disclosed in a previous application filed by me on May 20th, 1919, Serial No. 298,491.

15 The present invention has for an object to provide a simple and inexpensive attachment which will automatically remove the pressed flower or other article from the die.

For further comprehension of the invention, and of the objects and advantages thereof, reference will be had to the following description and accompanying drawings, and to the appended claims in which the various novel features of the invention 25 are more particularly set forth.

Figure 1 of the drawings is a side elevation of a press having the invention applied thereto.

Fig. 2 is a fragmentary front view on a 30 larger scale showing the attachment and a small portion of the press structure.

Fig. 3 is a detail transverse section, showing particularly the gripping jaws, this view being taken on the line 3—3 of Fig. 4.

35 Fig. 4 is a horizontal section on the line 4—4 of Fig. 2.

Fig. 5 is a detail section on the line 5—5 of Fig. 4 on a larger scale.

Fig. 6 is a fragmentary sectional elevation 40 showing the pawl carried by the presser head to operate the throw-out.

The press to which my invention is here shown applied, which press is disclosed in detail in the application above referred to, 45 comprises a table 1 having a standard 2 thereon in which is slidably mounted a block 3 carrying a punch head, or presser head 4. The block 3 is engaged by one end 5 of a bell crank lever 6 fulcrumed as at 7 to the 50 standard 2 and having a long depending arm operable by suitable means the precise nature of which has no relation to the present invention, this lever serving to operate the presser head.

55 Mounted on the table 1 is a guidebed 8 on which is slidably mounted a die carriage 9

having fixed thereon a die 10. This carriage is reciprocated horizontally in conjunction with the vertical reciprocation of the presser head, by means of a pair of levers 11 fulcrumed to brackets 12 depending from the table 1. The upper ends of these levers are connected to sleeves 13 slidable on rods 14 connected to the die carriage 9, the sleeves being disposed between compression springs 15 on the rods. The levers are each longitudinally slotted as at 16 and a transverse pin 17 carried on the main lever 6 bears at its ends in these slots.

My improved attachment comprises a pair 70 of jaws 20 and 21 having their jaw faces, indicated at 22, extending in a general vertical direction in the median line of the press. The jaw 21 is hinged upon the jaw 20 as at 23 and is normally held closed by 75 the tension springs 24 which are connected at opposite ends to the respective jaws. The jaw 20 is formed with an integral tail 25 by which it is secured on a rod 26 journaled in a bracket 27 fixed to the die carriage 9. A 80 coiled spring 28, which surrounds the rod 26 and bears at one end on the face of the die carriage and has its opposite end hooked over the jaw tail 25, serves to normally retain the jaws in the position shown in full 85 lines in Figs. 2 and 3, and to return the jaws to this position after operation by the throw-out means. In this position the jaw 20 rests on a cushion 20¹ upon the die carriage 9. The jaw 21 is provided with a tail 29 in 90 which is fixed a rod 30 adapted to bear against a post 31 projecting upwardly from the table 1 to open the jaws and release the flower when the jaws are swung by the throw-out means to the position shown in 95 dotted lines in Fig. 2.

The throw-out means comprises an arm 35 fixed to the projecting end of rod 26 and having mounted thereon a roller 36 adapted to be engaged by a cam face 37 on one 100 arm of a bell crank lever 38, fulcrumed on a pin 39 journaled in a second bracket 40 on the die carriage 9. The opposite arm 38¹ of this lever has fixed thereon a pin 41 which is adapted to be engaged by a 105 pawl 42 pivoted between the forked lower ends of an angular arm 43 fixed to the block 3. The pin 41 is so disposed with reference to the pawl 42 as to project at its end across the path of travel of the pawl which normally projects outwardly from the arm 43, being maintained in this position by a 110

spring 44, the pawl being mounted so as to swing upwardly against the action of spring 44 but being prevented from swinging down below the horizontal position by means of 5 a plate 45 fixed to the said forked lever ends of arm 43.

The operation is as follows: Levers 6 being reciprocated, the die carriage 9 is likewise reciprocated through levers 11 and 10 rods 14. When the die carriage is in its outermost position the flower to be pressed is inserted in the die and the stem thereof is simultaneously placed between the jaws 20 and 21 which may be opened slightly by 15 pressing down with the hand on rod 30. In Fig. 4 of the drawing the flower is indicated at 50 in position in the die and the stem 51 thereof is shown extending between the jaws. When the die moves inwardly 20 it stops under the presser head 4 which keeps on descending. In this position the end of pin 41 is in the path of travel of pawl 42 which swings backward to pass the pin and then returns to normal position. 25 As the presser head ascends the pawl engages the pin, the parts being so arranged that the presser head will have lifted clear of the die before this happens. As the pawl strikes the pin it swings the arm 38 of the 30 bell crank lever downward with a rapid snapping motion and the cam 37 thereon rides on roller 36 and swings arm 35, and with it the jaws. When the lever 38 swings downward the pin 41 is moved laterally to clear the pawl, the face of which is preferably beveled as at 42¹.

The momentum imparted to the jaws causes them to swing over to the position shown in dotted lines in Fig. 2, and, as the 40 rod 30 strikes the post 31, the jaws are

opened and the stem, or other article, thrown out. The springs 24, it will be noted, serve the double purpose of closing the jaws again and of cushioning the impact as the latter are brought to a stop by post 31. As will 45 be understood the lost motion between the levers 11 and rods 14 which is provided by the springs 15, causes the die carriage 9 to remain at rest until the presser head has cleared the die in its upward movement. 50 The jaws are returned automatically to their starting position by the coiled spring 28 while the cam lever 38 is prevented from being thrown an undesirable distance upward as the roller 36 reengages therewith, 55 by the pin 41 bearing on the top of the block 40 to which the cam lever is fulcrumed.

Claim:

In a press, a die, a reciprocatory carriage on which said die is mounted, a presser head, 60 a jaw member pivoted on said die carriage, a second jaw member pivoted on the first jaw member, resilient means holding said jaw members closed, a cam-faced lever adapted to cause said jaw members to 65 swing on the pivot of the first jaw member, a pawl carried with the presser head and adapted to engage and operate said lever when the presser head is ascending, and means for causing said jaws to open when 70 so swung, said means comprising a stop adapted to be engaged by a projection on the second mentioned jaw member.

Signed at city of New York, in the county of New York and State of New York 75 this 20th day of Oct. A. D. 1919.

SAMUEL THOMAS WALKUP.
